COMBINATION TRASH RECEPTACLE AND HOLDING CART

Thomas Ferarra, 1154 Webster Ave.,
New Rochelle, N.Y. 10804

Filed Dec. 6, 1968, Ser. No. 14,832

Term of patent 14 years

Int. Cl. D12—14; D7—06
U.S. Cl. D49—32

FIGURE 1 is a perspective view of a combination trash receptacle and holding cart showing my new design;

FIGURE 2 is a side elevational view thereof;

FIGURE 3 is a side elevational view thereof with the tray at the bottom, the removable bag and cover elements removed.

FIGURE 4 is a side elevational view as seen from the right-hand portion of FIGURE 2;

FIGURE 5 is a side elevational view as seen from the right-hand portion of FIGURE 3;

FIGURE 6 is a top plan view thereof;

FIGURE 7 is a bottom plan view thereof; and

FIGURE 8 is a top plan view as seen from the upper portion of FIGURE 5.

I claim:

The ornamental design for a combination trash receptacle and holding cart, substantially as shown and described.
